UNITED STATES PATENT OFFICE.

WASHINGTON I. PHIFER, OF COLLINSVILLE, ILLINOIS.

INTERNAL-COMBUSTION ENGINE.

1,087,681.

Specification of Letters Patent Patented Feb. 17, 1914.

Application filed August 21, 1912. Serial No. 716,125.

To all whom it may concern:

Be it known that I, WASHINGTON I. PHIFER, a citizen of the United States of America, residing at Collinsville, in the county of Madison and State of Illinois, have invented certain new and useful Improvements in Internal-Combustion Engines, of which the following is a specification.

10 The primary object of this invention is in providing an improved arrangement of parts whereby the cylinders and other working parts are all inclosed in one casing, thus making a compact and powerful motor, and 15 by an improved arrangement of power transmitting from the pistons and the crank shaft, the knocking of the moving parts is eliminated.

20 A further object is in providing means whereby the power derived from a number of cylinders of an internal combustion motor is transmitted to the crank shaft by a single connecting rod.

25 A further object is in providing improved means whereby the throw of the piston connecting rods is practically ~~the~~ away with; thus avoiding the side lash of the pistons on the cylinders.

30 A still further object is in providing improved means of lubrication to the pistons, cylinders and other working parts of an internal combustion engine.

35 Another object is in providing a uniform cooling temperature to a number of cylinders of an internal combustion engine, by having a single casing cover and containing all of said cylinders, so that the water surrounding said cylinders will be in one body.

40 Another object is in providing an improved rotary valve in which a single valve controls the supplying and exhausting of any number of cylinders of an internal combustion engine; said valve being always in receiving communication with the charging 45 mixture, and in exhausting communications with the exhaust discharge pipe.

50 Other and further objects will appear in the specifications and be specifically pointed out in the appended claims, reference being had to the accompanying drawings exemplifying the invention, and in which—

55 Figure 1 is a side elevation of this improved engine showing the connecting rod side. Fig. 2 is a plan view of Fig. 1 with the casing cover removed. Fig. 3 is a horizontal section taken on the line III—III of

Fig. 1. Fig. 4 is an enlarged vertical section through this improved engine taken approximately on the line IV—IV of Fig. 1. Fig. 5 is an enlarged vertical cross section taken approximately on the line V—V of Fig. 4. Fig. 6 is an enlarged side elevation of the improved rotary valve used in this improved engine. Fig. 7 is an end view of Fig. 6 taken in the direction of the arrow 7. Fig. 8 is an end view of Fig. 6 taken in the direction of the arrow 8. Fig. 9 is a vertical cross section taken on the line IX—IX of Fig. 6. Fig. 10 is a side elevation of Fig. 6 taken in the direction of the arrow 10. Fig. 11 is a plan view of an improved packing ring used in connection with the improved rotary valve.

In the drawings the bedplate 1 has mounted thereon the casing 2 which is positioned by the cap-screws 3. Located in said casing 2, and mounted on said bedplate 1, are a series of open ended cylinders 4 which are held in position by the cap-screws 5.

Reciprocably mounted in the cylinders 4 are pistons 6, said pistons being mounted on wrist-pins 7, to which are connected connecting rods 8; said connecting rods being connected to walking beams 9, mounted on a horizontal shaft 10 by the pins 11. Formed in the walls of the casing 2 adjacent the ends of the horizontal shaft 10, are bearings 12, in which said horizontal shaft is mounted, said shaft being held in position by the bearing caps 13. Mounted on horizontal shaft 10 adjacent one end, and on the outside of the casing 2, is a crank 14 having a crank pin 15, and connecting with said crank pin is a connecting rod 16, which connecting rod 16 is mounted to crank pin 17; carried by a crank 18 which is mounted on the end of a driving shaft 19, which is mounted in bearings 20. Formed in the side walls of the casing 2 adjacent its lower end, mounted on the driving shaft 19 on the opposite side of the casing 2, to which the crank 18 is mounted is a fly wheel 21, and mounted on the shaft 19 between said fly wheel 21, and casing 2, is a sprocket 22, on which is mounted a driving chain 23, said driving chain connecting with a sprocket 24; which sprocket is mounted on an end of a horizontal shaft 25.

The end wheels 26 of valve housing 27, serve as bearings for the said horizontal shaft 25, and located in said valve housing and mounted on the shaft 25, is a rotary valve 28, said valve being hollow and of a

drum shape, and has a spirally arranged partition or dividing web 28^a extending the length of said rotary valve 28, forming chambers 29 and 30. Formed in the periphery of the rotary valve 28 and communicating with the chamber 29 are ports 31 and 32, said ports communicating with the chamber 29, and forming intake ports, said ports 32 communicating with the chamber 30 forming exhaust ports. Formed in one end of the chamber 29 is an end wall 33, and formed at one end of the chamber 30 is an end wall 34.

By an inspection of Fig. 4 of the drawings, it will be noted that the rotary valve 28 is located at a distance away from the end walls 26 of the valve housing 27 forming end chambers 35 and 36. Located on the periphery of the rotary valve 28 adjacent the ends thereof, are packing-rings 37. Formed in the end wall 26 adjacent the end chamber 35, and at the bottom thereof is an intake pipe opening 38; and formed in the opposite end wall 26 adjacent the end chamber 36 is an exhaust pipe opening 39. Formed in the valve housing 27 and disposed up-wardly at an angle of about 45° from the center of the rotary valve 28, are inclined cylinders 40, said cylinders extending from the periphery of said valve to the bedplate 1. Located in said cylinders 40 and bearing against the periphery of the rotary valve 28, are valve packing-rings 41, carrying the cylinder bearing rings 42, said valve packing-rings 41 having a center opening 43 and pressure bearing surfaces 44. Formed in the bedplate 1, between the firing cylinders 4 and cylinders 40 are openings 45, which form means of communication between said cylinders, mounted on top of the casing 2, is a cover 46, which is held in place by the cap-screws 47, and is removable for the purpose of inspecting the moving parts contained therein.

In the operation of this improved internal combustion engine, assuming that the opening 38 located in one of the end walls 26 of the valve housing 27 has an intake pipe located therein, said intake pipe being for the charging mixture supply, the chamber 29 will be continually filled with the charging mixture, and as the rotary valve 28 is rotated the ports 31 communicating with the chamber 29 will be brought in communication with the cylinders 40; and at this point of the intake port communication, the piston 6 which will then be at the lower end of the cylinder 4 will be adjacent this port opening, and at a point of moving upwardly, a charge of mixture will be drawn from the chamber 29 through the port opening 31 into the cylinder 40, and to firing cylinder 4 through opening 45. By the time that the piston 6 has reached the end of the suction stroke, the port 31 will have closed, then as

the piston 6 moves on down-wardly compression in the cylinder 4 is obtained, and after the compression has taken place the point of firing is reached which will propel the piston back to the upward end of its stroke, at which point the piston begins to descend to scavenge the cylinder. By this time one of the exhaust ports 32 which has communication with the chamber 30 of the rotary valve 28, is in communication with the cylinder 4 through the cylinder 40 and opening 45, so that the descending piston 6 will discharge the burnt gases out into the chamber 30 of the rotary valve 28; and from there they will be carried on out through the exhaust pipe opening 39, located in the end wall 26 of the valve housing 27.

From an inspection of Fig. 4 of the drawings and with reference to the valve housing 27 and valve 28 it is to be noted that by reason of the chamber 35 formed in the end of the valve housing adjacent the intake opening 38, the chamber 29 formed in the valve 28 will be in continuous communication with the charging mixture, so that as the ports which communicate with said chamber 29, are brought into communicating position with the cylinders 40, the charging mixture is allowed to enter the cylinders to be charged. The chamber 36 formed in the end of the valve housing 27 adjacent the exhaust pipe opening 39, forms means of continuous communication of the chamber 30 with the exhaust pipe opening 39.

It is to be noted that the ports 31 and 32 are in communication with the chambers 29 and 30 respectively of the valve 28, which are located about 90° apart in the periphery of said valve and are in alinement with each other, and with the pair of cylinders 40, so that as said valve 28 is rotated the intake port 31 will communicate with first one cylinder 40 and then the other, the exhaust port 32 will in turn communicate with said cylinders. As shown there are 2 sets of ports 31 and 32 located on the periphery of the valve 28, one set of said ports being diametrically opposed from the other set, and are formed on the opposite end of the valve 28 on the periphery thereof. This set of intake and exhaust ports is for the purpose of operating on another pair of the cylinders 40 as shown. Inasmuch as there are 4 cylinders shown (2 pair) the relation of the 2 sets 31 and 32 is essential in order to take care of the firing cylinders in their order of firing, and to accommodate the ports 31 and 32 in relation to the chambers 29 and 30, the partition 28^a is spirally arranged through the valve 28. It is obvious that if a greater multiple of firing cylinders were used this rotary valve would only have to be made longer to accommodate additional intake and exhausting ports.

It is readily seen how the connecting rods 8 being mounted to the pistons 6 and walking beams 9, being connected to the horizontal shaft 10, will actuate or rock said shaft, then the crank 14 mounted outside of the casing 2 on one end of said shaft 10, will actuate the connecting rod 16 which connecting rod being connected at its lower end to the crank pin 17 of the crank 18, which 10 crank is mounted on the end of the driving shaft 19 will operate said driving shaft. With this improved manner of operation the connecting rods 8, being connected to the walking beams 9, the throw of the stroke 15 of said walking beams is slight, which will practically eliminate the lateral movement to the connecting rods 8. Therefore the side lash to the pistons of said connecting rods 8 will be eliminated, and the wear on the pistons and cylinders will be true.

Inasmuch as the rock shaft 10 is actuated by the connecting rods and walking beams, it will then only be necessary to have only one connecting rod to transmit the power 25 from the rock shaft to the driving shaft 19. This one connecting rod in connection with the driving shaft, which in transmitting power from a number of cylinders is a decided improvement over the construction of 30 the internal combustion engines, that now have connecting rods from the pistons to the cranks, as the duty of a connecting rod is heavy, and has to contend with severe knocking and jarring which loosens the connection of the connecting rods and the cranks; whereas with using only one connecting rod for a number of cylinders as shown the wear 35 will be confined to this one connecting rod, and as said connecting rod is assembled on 40 the outside of the casing 2, it is readily accessible for adjustment and repair. In having a number of cylinders incased by one casing, the water which is used for cooling the cylinders being contained in said casing 45 and surrounding said cylinders will be in one body, and the temperature in said body of water will be uniform.

In providing an improved form of lubrication, lubricating oil is poured into the casing 2, and on the water contained therein, and after the water becomes heated the oil 50 will mix with the water and vapor will arise therefrom and the oil laden vapor or steam will penetrate the working parts, and which 55 will provide a perfect lubrication thereto.

To prevent the water in the casing 2 from becoming too highly heated, it is to be understood that said water will be circulated through a radiator, such as is now in common use.

In the construction of this improved internal combustion engine as shown and described, a compact and efficient motor can be had, the moving parts being in easy access 60 of inspection by removing the cover 46.

In order to provide improved packing means to this improved rotary valve, valve packing rings located and movably mounted in the inclined cylinders 40, rest on the periphery of the rotary valve 28, so that when the compression and the exploding 70 of the cylinders 4 take place the pressure bearing faces 44 of the valve packing ring 41, press said valve packing ring down tightly. On the periphery of said valve 28 75 which will prevent escapement of the compression and firing force along the periphery of the rotary valve, the packing rings 37, located on the periphery of the valve 28 adjacent the ends thereof, are for the purpose 80 of packing said valve against the escapement of the charging mixture from the chamber 35, and also from the escapement of the burnt gases from the chamber 36. Also by reason of these packing rings 37 85 bearing against the inside walls of the housing 27 of the valve 28, will answer as packing as above stated. The outside diameter of the rotary valve 28 can be made of smaller diameter than the inside diameter of 90 the valve housing 27, and the rotary valve 28 being mounted on the shaft 25, will allow for the valve to be of easy running, as the only point of frictional contact of said valve against the valve housing will be the packing rings 37; and by reason of said valve 95 being of smaller diameter than the inside diameter of the housing, said valve will not have a tendency to bind by reason of the expansion caused by the exhausting of the 100 burnt gases through said valve. This valve housing is waterjacketed, and has communication with the water contained in the casing surrounding the firing cylinders.

What I claim is:

1. In an internal combustion engine the combination of a series of cylinders located therein, said cylinders arranged in pairs, pistons carrying connecting rods reciprocating in said cylinders, said connecting rods being connected to walking beams of a rock shaft, a casing inclosing said cylinders, rock shaft, walking beams, and connecting rods, a crank mounted outside of said casing on said rock shaft, said connecting rod connected to said crank, said connecting rod being connected at its opposite end to a crank on a driving shaft, said casing forming a water jacket around said cylinders, and forming a means of lubrication to the moving parts, mounted in said casing when oil is mingled with the water contained in said casing.

2. An internal combustion engine comprising a series of vertical cylinders located in a housing, the upper end of each of said cylinders being in communication with said housing, said housing adapted to form a space around said cylinders, and a shaft located in said housing above said cylinders, said shaft adapted to be actuated by pistons 125

- 1 and connecting rods operable from said cylinders, a second shaft located in said housing adjacent the lower end of said cylinders, and a rod connecting said shafts located at one end thereof, said connecting rod being located outside of said housing.
- 5 3. In an internal combustion engine, a vertical cylinder, a housing inclosing said cylinder having a base, and a removable wall, the lower end of said cylinder forming the firing end being mounted on said base, the upper end of said cylinder being in communication with said housing, said housing serving as a water jacket for said cylinder.
- 10 4. In an internal combustion engine, a vertical cylinder, a housing inclosing said cylinder having a base and a removable wall, the lower end of said cylinder forming the firing end being mounted on said base, the upper end of said cylinder being in communication with said housing, said housing serving as a water jacket for said cylinder, a rock shaft horizontally arranged above said cylinder in said housing, a piston reciprocably mounted in said cylinder, and a rod connecting said piston with said rock shaft, a crank shaft located in said housing adja-
- cent the firing end of said cylinder, and a connecting rod located outside of said housing connecting said rock shaft and the crank 30 shaft of said crank shaft.
5. In an internal combustion engine, a pair of vertical cylinders, a housing inclosing said cylinders having a base and a removable wall, said cylinders being secured 35 to said base at their lower ends, the lower ends of said cylinders forming the firing chambers, the upper ends of said cylinders being in communication with said housing, a rock shaft horizontally arranged above 40 said cylinders in said housing, pistons in said cylinders, rods connecting said pistons with said rock shaft, a crank shaft located in said housing between said cylinders adjacent the lower end thereof, and a connecting rod located outside of said housing connecting said rock shaft and the crank of said 45 crank shaft, said housing adapted to form a water jacket for said cylinders.

WASHINGTON I. PHIFER.

In the presence of—
H. G. FLETCHER,
L. KLEINTOPF.
